US00D741592S

(12) United States Design Patent
Shainwald et al.

(10) Patent No.: US D741,592 S
(45) Date of Patent:  Oct. 27, 2015

(54) BOW MAKER

(71) Applicant: EK Success, Ltd., Woodridge, IL (US)

(72) Inventors: Mark Shainwald, Woodridge, IL (US);
David Starr, Woodridge, IL (US);
Heather Rohlfs, Woodridge, IL (US);
Luke Li, Shenzhen (CN)

(73) Assignee: EK SUCCESS LTD., Clifton, NJ (US)

() Term: 14 Years

(21) Appl. No.: 29/504,975

(22) Filed: Oct. 10, 2014

(51) LOC (10) Cl. 02-07

(52) U.S. Cl.

USPC D3/26

(58) Field of Classification Search

USPC D15/66, 78; D3/18, 26; D19/108

CPC D04D 7/10; D04D 11/00

(57) CLAIM

We claim the ornamental design for a bow maker, as shown and described.

DESCRIPTION

FIG. 1 is a perspective view of a bow maker according to the new design;

FIG. 2 is a top plan view of the bow maker shown in FIG. 1; FIG. 3 is a bottom plan view of the bow maker shown in FIG. 1;

FIG. 4 is a side view of the bow maker shown in FIG. 1; FIG. 5 is a side of the bow maker shown in FIG. 1; FIG. 6 is a side view of the bow maker shown in FIG. 1; and, FIG. 7 is a side view of the bow maker shown in FIG. 1. The portions of the article in broken lines are shown for illustrative purposes and form no part of the claimed design.

1 Claim, 3 Drawing Sheets
